CARTON DISPENSER

Filed March 16, 1928

INVENTOR
WALDEMAR A. ENDTER

by *H. A. Dreckman*
ATTORNEY.

UNITED STATES PATENT OFFICE.

WALDEMAR A. ENDTER, OF LONG BEACH, CALIFORNIA.

CARTON DISPENSER.

Application filed March 16, 1928. Serial No. 262,188.

This invention relates to a dispenser for paper pails such as those used for oyster, ice cream, pickles, and other supplies which are vended by the delicatessen store and the like.

An object of my invention is to provide a dispenser in which pails of various sizes can be readily accommodated.

Another object is to provide a container in which the pails are held in a sanitary condition and which are readily accessible to the clerk.

A further object is to provide a dispenser which can be adjusted to accommodate pails of slightly different sizes.

Other objects, advantages, and features of invention may appear from the accompanying drawing, the subjoined detailed description, and the appended claims.

In the drawing—

Fig. 1, is a front elevation of my vending cabinet with parts broken away.

Fig. 2, is a bottom plan view of the same.

Fig. 3, is a side elevation.

Fig. 4, is a sectional view taken on line 4, 4 of Figure 1.

Fig. 5, is an enlarged fragmentary longitudinal sectional view on line 5, 5 of Figure 1.

Referring more particularly to the drawing:

The numeral 1 indicates my cabinet in which a plurality of longitudinally extending compartments 2 are provided. Partition walls 3 in the cabinet separate the various compartments. A front wall 4 extends to adjacent the bottom of a space at the cabinet but the lower end is left open, as at 5, so that the pails can be vended therethrough.

An adjusting plate 6 is mounted on the rear wall of the cabinet in each of the compartments 2 and the adjusting plate is adapted to be moved inwardly into the compartment constricting the lower opening thereof and thus forcing the pails towards the front wall 4 for a purpose to be further described.

The plates 6 are each provided with a notch 7 therein across which the plates bend and this notch is about in line with the lower edge of the front wall 4. To provide the necessary adjustment of the plate 6 a screw 8 screws through the front edge thereof, said screw being threaded into a stationary nut 9 secured to the rear wall of the cabinet. The top of the plate 6 rests against the top of the cabinet and thus it will be seen that when

such adjustment is effected to pull out the

front edge of the plate 6, the front edge of the

plate 6 will buckle upwardly across its base

between the notches 7, thus constricting the

compartment 2 and causing the pails to be moved against the front wall of the cabinet.

A hollow, metal molding 10 is secured to the front wall 4 at the bottom thereof. This molding extends across the entire cabinet and is welded, bolted or otherwise secured thereto. The purpose of this molding is to

mount the yieldable fingers 11 against which the bottom pail rests.

A pair of spring fingers 11 are provided in each of the compartments 2 and these fingers project inwardly into the compartment 2 at the bottom of the front wall 4.

The fingers 11 are suitably secured at one end under the hollow molding 10 such as by bending the upper end of the finger over the molding as shown at 11' and

bottom end of the fingers are bent upwardly, as at 12, and this bent part extends through a slot 13 in the molding, the bent edge 12 thus limits the inward movement of the fingers.

An inwardly projecting lug 14 is formed on each of the fingers and the flap of the lower-most pail rests upon this lug, as shown in Figure 5.

In actual use my cabinet is hung on a wall, as shown in Fig. 1, and the oyster pails, or the like, 15, are nested one on the other and are placed in each of the compartments 2 with the top open end of the pails facing downwardly. The front flap 16 of the lower-most pail rests upon the lug 14 of the spring fingers 11. When it is desired to remove one of the pails the front flap 16 is pushed inwardly, thus removing it from the fingers 11 and the pail is then pulled downwardly through the opening 5 and the next adjacent pail is pulled downwardly and is stopped by the lugs 14 which engage its front flap 15.

The fingers 11 will yield due to their spring construction to permit the pail to be removed from the cabinet but the lugs 14 will always drag against the pail during its removal so that the flap 16 of the next adjacent pail will be engaged as that pail is pulled downwardly.

Having described my invention, I claim:

1. A dispenser for oyster pails and the like comprising a cabinet having front and rear walls, an opening at the bottom of the cabinet through which the pails are dispensed, spring

fingers secured to said front wall adjacent the bottom thereof, said fingers being adapted to

105

drag against the pail during its removal so that the flap 16 of the next adjacent pail will

be engaged as that pail is pulled downwardly.

Having described my invention, I claim:

1. A dispenser for oyster pails and the like comprising a cabinet having front and rear walls, an opening at the bottom of the cabinet through which the pails are dispensed, spring fingers secured to said front wall adjacent the bottom thereof, said fingers being adapted to

110

engage the flap of the pail to limit the downward movement thereof, an adjusting plate in the cabinet extending the length thereof, and means engaging the front edge of the plate whereby the same is buckled to constrict the passage between the front and rear walls of the cabinet to accommodate different sized pails.

2. A dispensing cabinet for oyster pails, 10 and the like, having a plurality of compartments therein, front and rear walls on the cabinet, spring fingers adjacent the bottom of the front wall adapted to engage the front flap of the pails which are positioned in the 15 compartment, a hollow molding under which the spring fingers are held, and a lip on the spring fingers positioned inside of the hollow molding whereby the inward movement of the fingers is limited.
3. A dispensing cabinet for oyster pails, 20 and the like, having a plurality of compartments therein, front and rear walls on the cabinet, spring fingers adjacent the bottom of the front wall adapted to engage the front flap of the pails which are positioned in the 25 compartment, a hollow molding under which the spring fingers are held, and a lip on the spring fingers positioned inside of the hollow molding whereby the inward movement of the 30 fingers is limited; an adjusting plate in each of the compartments, said adjusting plate extending the length of the cabinet, said plate having notches formed therein between which notches said plate is adapted to buckle, and means engaging the front of the plate to push the same upwardly and cause buckling of the plate to constrict the passage in the compartment.

4. A dispensing cabinet for oyster pails, 40 and the like, having a plurality of compartments therein, front and rear walls on the cabinet, spring fingers adjacent the bottom of the front wall adapted to engage the front flap of the pails which are positioned in the 45 compartment, a hollow molding under which the spring fingers are held, and a lip on the spring fingers positioned inside of the hollow 50 molding whereby the inward movement of the fingers is limited; an adjusting plate in each of the compartments, said adjusting plate extending the length of the cabinet, said plate having notches formed therein between which notches said plate is adapted to buckle, and means engaging the front of the plate to push the same upwardly and cause buckling of the plate to constrict the passage in the compartment.

5. A dispensing cabinet for oyster pails, 55 and the like, having a plurality of compartments therein, front and rear walls on the cabinet, spring fingers adjacent the bottom of the front wall adapted to engage the front flap of the pails which are positioned in the compartment, a hollow molding under which the spring fingers are held, and a lip on the spring fingers positioned inside of the hollow 60 molding whereby the inward movement of the fingers is limited; an adjusting plate in each of the compartments, said adjusting plate extending the length of the cabinet, said plate having notches formed therein between which notches said plate is adapted to buckle, and means engaging the front of the plate to push the same upwardly and cause buckling of the plate to constrict the passage in the compartment.

molding whereby the inward movement of the fingers is limited, an adjusting plate in each of the compartments, said adjusting plate extending the length of the cabinet, said plate having notches formed therein between which notches said plate is adapted to buckle, a screw extending through the front edge of the plate, a nut secured to the rear 55 wall into which the screw is adapted to be threaded whereby the plate can be adjusted to constrict the passage in the compartment.

5. A dispenser for oyster pails and the like, comprising a cabinet having front and 60 rear walls, an opening at the bottom of the cabinet through which the pails are dispensed, spring fingers secured to said front wall adjacent the bottom thereof, said fingers being adapted to engage the flap of the pail to limit 65 the downward movement thereof, a plate in the cabinet, a bolt extending through the front edge of the plate, a nut secured to the cabinet into which the bolt is adapted to screw whereby the plate is adjusted to constrict the 70 passage in the cabinet.

6. A dispenser for oyster pails and the like, comprising a cabinet having front and 75 rear walls, an opening at the bottom of the cabinet through which the pails are dispensed, spring fingers secured to said front wall adjacent the bottom thereof, said fingers being adapted to engage the flap of the pail to limit 80 the downward movement thereof, a plate in the cabinet, a bolt extending through the front edge of the plate, a nut secured to the cabinet into which the bolt is adapted to screw whereby the plate is adjusted to constrict the passage in the cabinet, said plate having notches formed therein between which 85 the plate is adapted to buckle, and spring outwardly into the cabinet to constrict the passage therein, a hollow molding under which the fingers are secured, and a lip on the fingers within the molding whereby 90 the inward movement of the fingers is limited.

In testimony whereof, I affix my signature.

WALDEMAR A. ENDTER.
